DESIGN FOR A LANTERN

Philip Silberhartz, Maywood, N. J., assignor to Artolier Corporation, Lodi, N. J., a corporation of New York

Application August 5, 1947, Serial No. 140,705

Term of patent 3½ years

(Cl. D48—24)

To all whom it may concern:

Be it known that I, Philip Silberhartz, a citizen of the United States of America and a resident of Maywood, in the county of Bergen and State of New Jersey, have invented a new, original, and ornamental Design for a Lantern, of which the following is a specification, reference being had to the accompanying drawings, forming a part thereof.

In these drawings:

I claim:

The ornamental design for a lantern, as shown.
PHILIP SILBERHARTZ.
